UNITED STATES PATENT OFFICE.

ALBERT W. BARTHOLOMEW, OF MANCHESTER, NEW HAMPSHIRE.

AXLE-TOOL.

SPECIFICATION forming part of Letters Patent No. 320,748, dated June 23, 1885.

Application filed August 6, 1884. (No model.)

To all whom it may concern:

Be it known that I, ALBERT W. BARTHOLOMEW, a citizen of the United States, residing at Manchester, in the county of Hillsborough 5 and State of New Hampshire, have invented certain new and useful Improvements in Axle-Tools; and I do hereby declare the following to be a full, clear, and exact description of the invention, such as will enable others skilled in the art to which it appertains to make and use 10 the same.

This invention relates to improvements in axle-tools, whereby any form or size of metallic axles may be speedily and properly repaired or altered. It is often found that the 15 axles of vehicles become after a time so much worn as to cause the wheels to rattle on the axles, necessitating the use of washers between the hub of the wheel and the axle-nut; but a better and more effectual way is to turn 20 up a new shoulder and to cut a new thread to correspond, and also, if necessary, to cut off a portion of the end of the axle.

The object of my invention is to provide a 25 cheap, simple, and effective tool for this purpose, and one easily managed by artisans who are required to do such work. This I do by means of the mechanism illustrated in the accompanying drawings, in which—

30 Figure 1 represents a side elevation, Fig. 2 a front elevation, and Fig. 3 a rear elevation, of the tool.

A represents the stock or body of the tool, having a recess, E, Fig. 2, for the purpose of 35 receiving a movable tool-block, B, and also a recess in the rear F, Fig. 1, for the purpose of receiving a pair of screw-cutting dies, D D'.

h is a cutting-tool, of steel, secured in the 40 tool-block B by means of the movable clamp or strap g and screws k k'.

H is a stand attached to the stock A for the purpose of supporting the yoke f.

m m' are check-nuts to secure the stock to 45 the axle when the cutting-tool h is being used.

K K' are stands attached to the stock A for the purpose of supporting the yoke J and movable clamp O and check-nuts n n'.

C is a feed-rod passing through a bearing, 50 q, and secured to the tool-block B by means of the collar s and nut t.

p is a nut with inside screw to receive the feed-screw on the rod C.

a is a milled head for the purpose of operating the feed-screw C.

d is a feed-screw with milled head b passing 55 through the bearings u and w.

r is a nut-bearing to regulate the feed or cut of the dies D D'.

Similar letters refer to similar parts throughout the several views.

The manner of using the device is as follows: When an axle is to be repaired by turning up a new shoulder, the device is attached to the work by slipping the same over the end of the axle, with the cutting-tool h toward the 60 old shoulder of the same. The yoke J and movable clamp O are then brought to bear on the body of said axle and secured in place by means of the check-nuts n n'. The whole body of the stock is now made to revolve around 70 the work by means of the small part of the body of the stock, which may be of any desired length. Thus by means of the feed-screw C and cutter h the required amount of metal can be removed and a new shoulder 75 formed. Now reverse the device, bringing the rear side holding the dies D D' toward the shoulder, and secure the same loosely by means of the yoke f and check-nuts m m', and bring the dies D D' down to the work, regulating the cut by means of the feed-screw d, 80 and cut the screw up to the new shoulder by rotating the device in the same manner as when using the cutting-tool. If it is desired to cut off the end of the axle, that can be done 85 while the tool is in the latter position by feeding down the cutting-tool h as may be required.

Having thus described my invention, what I claim as new, and desire to secure by Letters 90 Patent, is—

1. In an axle-tool, the combination of stock A, provided with a guide-recess for the tool-block, and an adjustable guide-yoke, J, with tool-block B, cutter h, and feed-screw C, substantially as described.

2. In an axle-tool, the combination of stock A, provided with a recess for the dies, the dies D D', the latter provided with means for adjustment, and the yoke f, substantially as 100 set forth.

ALBERT W. BARTHOLOMEW.
